UNITED STATES PATENT OFFICE.

HAROLD CURTICE SANDERS, OF NEWPORT, ENGLAND.

ELECTRICAL DOUBLE-POLE SWITCHING PLUG.

Application filed April 23, 1921. Serial No. 463,985.

To all whom it may concern:

Be it known that I, HAROLD CURTICE SANDERS, a subject of the King of England, residing at 34 Bridge Street, Newport, in the county of Monmouth, England, whose post-office address is 34 Bridge Street, Newport, in the county of Monmouth, England, have invented certain new and useful Electrical Double-Pole Switching Plugs, of which the following is a specification.

This invention relates to a switching plug for the purpose of establishing and controlling electrical circuits. The switching plug is designed to provide a connection between any fixed point and such apparatus as are usually connected by flexible cord, and possesses the following advantages:—

- (a) The switch action provides a quick make and quick break on each pole.
- (a') The speed of make and break is entirely outside of the control of the operator.
- (b) The plug cannot be withdrawn unless the current is broken by quick action on each pole.
- (c) The plug cannot be inserted with the switch closed.
- (d) No live parts exposed to touch.

The switching plug comprises a base and a plug.

The base is constructed of a suitable insulating material carrying two metallic terminals and a cover of insulating material, or a metallic cover suitably lined. The base and cover are provided with a central hole to receive the plug, and the cover has two apertures in its face through which the plug contact blades enter.

The plug body is of insulating material and has a central hole provided for the reception of the flexible cable, the ends of which are attached to the plug contact blades. A loose handle is provided around the plug body to impart a semi-rotary motion thereto, a spring being contained in the said handle and adapted to wind clockwise or anti-clockwise, the ends of the spring being anchored, one to the said handle, and the other to the plug body or on the same fixed pin on the plug body. A locking pawl or spring catch is provided to prevent the plug body rotating until the spring is wound to the required extent, whereafter the said

pawl or catch is automatically withdrawn allowing the main spring to rotate the plug body during that part of a circle required to complete the aforementioned quick make or quick break.

The plug and base are so arranged that the plug contact blades themselves form the switch blades, which, on entering the apertures in the cover and receiving the said semi-rotary motion close the electrical circuit and prevent the withdrawal of the plug until its return to the "off" position, which is attained by the winding of the spring by the loose handle in the opposite direction to that used in closing the circuit.

In the accompanying drawings:—

Fig. 1 is a sectional elevation of my improved double pole rotary switching plug; 70

Fig. 2 is a plan of the same partly broken away to show the manner in which the ends of the spring are engaged by a pin on the loose handle A; and

Figs. 3 and 4 are sections taken on the lines 3—3 and 4—4 respectively in Fig. 1. 75

Fig. 5 is a view showing the plug in section to illustrate the structural relation between the handle, the plug, and the plug contacts. 80

Fig. 6 is a view showing the receptacle contact.

The same parts are lettered to correspond in all four figures.

My improved rotary switching plug comprises four principal parts, namely the rotor A, the loose handle B mounted on the rotor, the base C and the base cover D. 85

The rotor A carries two contact blades I diametrically located around the central cylindrical body of the rotor and adapted to engage with terminals H in the base C. These blades I are passed through apertures D', made in the base C and base cover D, and opening into an annular recess K in the base C in which recess the terminals H are secured in the ordinary way. The contact blades I are connected to flexible cables, wires, or the like leading to the apparatus to be electrically connected with the circuit containing the terminals H. 95

The rotor A carries a locking pawl or spring catch E mounted in a radial recess of housing E', (see Fig. 4) and engaging in a

keeper or notch F made to receive it in the base cover D thereby preventing rotation of the rotor until the pawl or catch is released.

Around a drum A' mounted on the upper 5 part of the rotor is loosely wound a coil spring A² the ends A⁴ of said spring being hooked on to opposite sides of one and the same pin A³ (see Fig. 2). The said pin A³ serves to connect together two plates G and 10 G', secured to the drum and the rotor, each of which carries, or is provided with, two projecting teeth or stops G⁸, between which plates the spring A² is located.

The loose handle B carries a pin B' which 15 passes between the projecting ends A⁴ of the spring and the said pin connects the loose handle B with a catch releasing plate L. This plate L is provided with cams or flat surfaces L' adapted when rotated to engage 20 the spring catch E and force same back out of the keeper or notch F in the base cover into its radial housing E'.

The operation is as follows:—The plug is 25 inserted into the base C by passing its contact blades through the apertures D' into the annular recess K. The handle B is then rotated which by means of the pin B' puts one end of the spring A² under tension while the other end remains stationary against 30 the fixed pin A³, the rotor A being held against rotary movement by the spring catch E engaging in the keeper F. When the handle has been rotated sufficiently to bring the cam or flattened surfaces L' against 35 the catch E the latter is depressed into its housing and the rotor thereupon rapidly rotates under the influence of the tensioned spring until the contact blades I engage in the terminals H in the base C, the spring 40 catch E resting in one of the apertures D', where it is again depressed into its housing by the reverse rotation of the loose handle B. It will be observed that the stops G⁸ on the plates G and G', prevent the pin B', 45 and consequently the loose handle B, from rotation beyond a quarter of a circle, the rotor making a similar movement of 90 degrees in the same direction after the movement of the handle has ceased.

50 I claim:—

1. An electric switch plug, including a base having a pair of contacts therein, a rotor provided with a pair of contacts for engagement with the contacts in the base 55 adapted for removable connection with the base when the contacts are out of engagement, means for locking said rotor against rotary movement in the base, a handle rotatably mounted on the rotor having means 60 for releasing the first-mentioned means, and operating means within the handle for rotating the plug after the handle has been rotated for releasing the first-mentioned means.

65 2. An electric switch plug, including a

base having a pair of contacts therein, a rotor provided with a pair of contacts for engagement with the contacts in the base and adapted for removable connection with the base when the contacts are out of engagement, means for locking said rotor against rotary movement in the base, and a handle rotatably mounted on the rotor containing means for releasing said locking means and rotating the rotor thereafter controlled by the rotary movement of the handle.

3. A detachable electric switch, comprising a base having a pair of contacts therein, a rotor removably mounted in the base and provided with the contacts in the base, a spring actuated latch carried by the rotor and engaging a seat in the base, a hollow handle formed with cam surfaces adapted to cooperate with the latch, a spring mounted on the rotor and housed within the handle, and means on the handle to engage the spring to place same under tension to rotate the rotor when one of the cam surfaces engages and releases the latch.

4. A detachable electric switch, comprising a base having a pair of contacts therein, a central recess, and slots extending from the recess disposed at points between the contacts, a rotor removably inserted in the recess in the base having a pair of switch blades thereon adapted to engage the contacts in the base and pass through said slots when the contacts are disengaged for the removal of the plug from the base, a spring pressed latch carried by the rotor and adapted to engage a notch in the base, a handle rotatably mounted on the rotor having means for releasing the latch, and resilient means mounted on the rotor and connected with the handle, and tensioned by the handle in the rotation thereof for rotating the rotor in the body when the means on the handle releases the latch from the notch in the body.

5. A detachable electric switch, comprising a base having a central recess, an annular recess communicating therewith, and oppositely disposed slots communicating with the annular recess, oppositely disposed contacts mounted in the annular recess in the base at right angles to the slots, a rotor rotatably and removably mounted in the central recess in the base having a pair of contact blades extending from opposite points on the periphery thereof for engagement with the contacts in the base and permitting the removal of the rotor from the base when opposite the slots, a spring pressed latch carried by the rotor for engagement in a recess in the base, a handle rotatably mounted on the rotor having cam surfaces adapted to engage the latch to release it from the recess in the base, and a spring member mounted on the rotor within the handle having the

end portions engaging on each side of a pin extending through the handle adapted to be tensioned by the rotation of the handle for turning the rotor in the base when a cam surface on the handle releases the latch from a notch in the base.

In testimony whereof I have hereunto set

my hand in presence of two subscribing witnesses this 30th day of March, 1921.

HAROLD CURTICE SANDERS.
